UNITED STATES PATENT OFFICE

2,446,012

COLLAR HOLDING CLASP

Louis Martin Kahn, Bronx, N. Y.

Application December 31, 1943, Serial No. 516,365

3 Claims. (Cl. 24—81)

1

This invention relates to new and useful improvements in a collar holding clasp.

More specifically, the invention proposes the construction of a collar holding clasp constructed of a single piece of material bent in a manner to form a back bar portion for extending across the back faces of the points of a collar and a front bar portion for extending across the front faces of the points of a collar with the bent portions being connected together at its center by a narrow support side portion to form a unit of the parts.

Still further it is proposed to provide the ends of the front bar portion with a loop-like clamp portion for engaging against the ends of the back bar portion in a manner to clamp the points of the collar in position between the adjacent face of the back bar portion and the loop-like clamp portions.

Still another object of the invention proposes the provision of a means for holding the loop-like clamp portions in various adjusted positions to control the resiliency with which the clamp portions will act with the back bar portion in engaging the points of the collar.

Still another object of the invention proposes characterizing the adjustment means for the loop-like clamp portions by prongs formed on the ends thereof selectively engageable with complementary apertures formed in the front bar portion in a manner to form the holding means for the clamp portions.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a collar holding clasp constructed in accordance with this invention.

Fig. 2 is an elevational view of Fig. 1.

Fig. 3 is an enlarged vertical sectional view on the line 3—3 of Fig. 2.

Fig. 4 is a perspective view of the blank from which the collar holding clasp is bent.

Fig. 5 is an elevational view of a collar holding clasp constructed in accordance with a modification of the invention.

Fig. 6 is a plan view of a collar holding clasp constructed in accordance with another modification of the invention.

2

Fig. 7 is an enlarged partial longitudinal sectional view taken on the line 7—7 of Fig. 6.

Fig. 8 is a plan view of the blank form which the clasp shown in Fig. 6 is formed.

The collar holding clasp, according to this invention, is formed from a resilient sheet of material 10 which has a back bar portion 11 for extending across the back faces of the points of a collar. The sheet 10 further includes a front bar portion 12 for extending across the front faces of the points of a collar and is connected at its center to the center of the back bar portion 11. This connecting means comprises a narrow side support portion 13 arranged between adjacent side portions of the back bar portion 11 and the front bar portion 12.

The opposite side edges of the back bar portion 11 and the front bar portion 12 are provided with projecting lugs 13a and 130a. These lugs 13a and 130a are adapted to be bent towards each other as illustrated in Fig. 3 to contact each other and provide a support for the free edges of the back bar portion 11 and the front bar portion 12.

As illustrated in Fig. 4, it will be noted that the back bar portion 11 and the front bar portion 12 are tapered from their center to their ends providing extra strength at the center of these portions to increase the resiliency thereof and securely maintain the loop portions 14 and 140 firmly in position.

The end portions of the front bar portions 12 are bent into loop-like clamp portions 14 and 140 which engage against the ends of the back bar portion 11. These loop portions 14 and 140 cooperate with the adjacent face of the back bar portion 11 in clamping the points of the collar in position upon the inside face of the back bar portion 11.

A developed view of the blank from which the collar holding clasp is bent is illustrated in Fig. 4. It will be noted that the back bar portion 11, the front bar portion 12, and the narrow side support portion 13 are of integral formation and the loop portions 14 and 140 continue from the ends of the front bar portion 12 requiring merely that the blank 10 be slightly bent to the position shown in Fig. 1.

In the modification of the invention shown in Fig. 5 the construction of the collar holding clasp is similar to that previously illustrated except for the formation of the loop portions 14' and 140'. In this form of the invention the loop portions are bent into a rounded configuration.

In other respects this form of the invention is similar to that previously shown and like refer-

ence numerals identify like parts in each of the several views.

In Figs. 6 to 8 the construction of the collar holding clasp is similar to that previously described, except for the provision of a means for holding the loop-like clamp portion 140' in various adjusted positions for controlling the resiliency with which these loop portions will engage the inside faces of the back bar portion 11. In this form of the invention the free ends of the loop-like clamp portions 140' are provided with projecting prongs 15 and 150 which are selectively engageable with complementary apertures 16 and 160 formed in the front bar portion 12. The prongs 15 and 150 may be engaged with any one of the projections 16 and 160 for controlling the shape of the clamp portions 14' and 140' and extending their shape with relation to the front bar portion 12 to bear more rigidly against the adjacent face of the back bar portion 11.

With the construction shown in Figs. 6 to 8, if the clasp fails to properly grip the points of a collar it is merely necessary to adjust the shape of the clamp-like portions 14' to bear more rigidly against the adjacent face of the back bar portion 11. In other respects this form of the invention is similar to that previously shown and similar reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A collar holding clasp, comprising a resilient sheet having a back bar portion for extending across the back faces of the points of a collar, a front bar portion for extending across the front faces of the points of said collar and connected at its center with the center of said back bar portion, loop-like clamp portions on the ends of said front bar portion and engaging against the ends of said back bar portion, and means for adjusting the resiliency of said loop-like clamp portions, comprising prongs formed on the ends of said loop-like clamp portions and selectively engageable with complementary openings formed in the ends of said front bar portion.
2. A collar holding clasp formed of a single piece of metal comprising a back bar portion for

extending along the back faces of the points of a collar, a narrow side support portion continuing from one side of said back bar portion and bent at right angles thereto, a front bar portion continuing from said side support portion and bent at right angles thereto to extend parallel to said back bar portion and along the front faces of the points of said collar, loop-like clamp portions continuing from the ends of said front bar portions and cooperating with the end portions of said back bar portion to clamp the points of said collar in position between said bar position, and means for preventing the free edge portions of said bar portions from being bent towards each other, comprising lug portions formed on the free edge portions of said bar portions, and bent towards each other, each of said lug portions being equal in length to one half the length of said support portion to contact each other when bent at right angles to their respective bar portions and towards each other.

3. A collar holding clasp formed of a single piece of metal comprising a back bar portion for extending along the back faces of the points of a collar, a narrow side support portion continuing from one side of said back bar portion and bent at right angles thereto, a front bar portion continuing from said side support portion and bent at right angles thereto to extend parallel to said back bar portion and along the front faces of the points of said collar, loop-like clamp portions continuing from the ends of said front bar portions and cooperating with the end portions of said back bar portion to clamp the points of said collar in position between said bar positions, and prongs on the free ends of said loop-like clamp portions selectively engageable with one of a plurality of complementary openings formed in the ends of said front bar portion for holding said clamp portions in desired adjusted positions.
